(57) **CLAIM**

The ornamental design for the bucket with external organizer, as shown and described.

DESCRIPTION

FIG. 1 is top perspective view of the bucket with external organizer;

FIG. 2 is first bottom perspective view of the bucket with external organizer;

FIG. 3 is a second bottom perspective view of the bucket with external organizer;

FIG. 4 is a front view of the bucket with external organizer;

FIG. 5 is a back view of the bucket with external organizer;

FIG. 6 is right side view of the bucket with external organizer;

FIG. 7 is left side view of the bucket with external organizer;

FIG. 8 is a top view of the bucket with external organizer; and,

FIG. 9 is a bottom view of the bucket with external organizer.

The broken lines showing portions of the bucket with the external organizer form no part of the claimed design.

1 Claim, 9 Drawing Sheets
